CURTAIN SUPPORTING DEVICE

Filed Jan. 6, 1925

2 Sheets-Sheet 2

UNITED STATES PATENT OFFICE.

EVERETT A. BURNS, OF CHICAGO, ILLINOIS.

CURTAIN-SUPPORTING DEVICE.

Application filed January 6, 1925. Serial No. 863.

To all whom it may concern:

Be it known that I, EVERETT A. BURNS, a citizen of the United States, residing at Chicago, in the county of Cook and State of Illinois, have invented certain new and useful Improvements in Curtain-Supporting Devices, of which the following is a specification, reference being had to the accompanying drawings.

10 This invention relates to devices for holding curtains at windows, and particularly to devices adapted to be applied as a whole to the window casing at opposite sides thereof and which afford means for supporting the ordinary shade and curtains of a window.

One of the objects of my invention is to provide a simple, neat and effective device of this character which is readily attachable to or detachable from the window casing and which is so designed as to support the regular window shade and curtain and a plurality of "drapes."

20 A further object of the invention is to provide a device of this character which is readily adjustable so as to suit different widths of windows and which is particularly adapted to be used in windows where the casing is relatively deep and where shades 25 are disposed between the jambs of the window.

A still further object is to provide means whereby the devices for supporting the main shade roller or rod may be adjusted toward 30 or from each other as desired and held in these adjusted positions.

Another object is to provide a device of this character which is so constructed that adjustment may be made for window shade 40 rollers of different lengths.

Still another object is to provide detachable means whereby curtain rods may be supported for the valance, side curtains, and "drapes" of a window.

45 Other objects will appear in the course of the following description.

My invention is illustrated in the accompanying drawings, wherein:—

Figure 1 is a front view of the upper portion 50 of a window casing showing my device in place but with the curtains omitted to display the parts of the device;

Figure 2 is a horizontal sectional view

through one form of a window casing showing my device applied thereto;

55 Figure 3 is a front elevation of one of the curtain roller supports;

Figure 4 is a rear elevation of the same partly broken away;

Figure 5 is a section on the line 5—5 of 60 Figure 3;

Figure 6 is a section on the line 6—6 of 65 Figure 5;

Figure 7 is a section on the line 7—7 of 70 Figure 4;

Figure 8 is a section on the line 8—8 of 75 Figure 4;

Figure 9 is a perspective view of the block with which the curtain support is slidably engaged, this block being intended to be 80 attached to the window casing;

Figure 10 is a perspective view of one of the shade brackets;

Figure 11 is a perspective view of the means for supporting a series of upper 85 curtain rods;

Figure 12 is a fragmentary perspective view showing one end of one of the curtain rods;

Figure 13 is a perspective view of the 90 block 36^a which is adapted to be disposed in masonry or brickwork.

Referring to these drawings, it will be seen that I have illustrated in Figures 1 and 2 a window casing having a facing frame 85 A and a deeply recessed jamb B. The window shade C is disposed between these jambs B and inward of the facing A of the frame. While I have illustrated this form of window casing to show the application of my 95 device, I do not wish to be limited thereto as the device is equally applicable to other forms of window casing.

My device comprises two like members adapted to be disposed on each side of the 95 window frame at the upper corners thereof and particularly against the facings A. One of these devices is illustrated in Figures 3, 4, 5 and 6, and each device comprises a front plate 10 which is transversely 100 rounded, as shown in Figure 6, and which may be made of any suitable material as, for instance, metal or wood. This casing 10 is hollow and attached to the rear face of the casing are the two longitudinally extending strips 11 which may be formed in-

tegral with the casing or soldered thereto or formed in any suitable manner. These strips 11 are separated from each other along their inner edges to form a longitudinally extending slot 12, this slot being enlarged at its lower end, as at 13. The upper portion of the face plate 10 is curved downward and inward, as at 14, this portion 14 not extending entirely across the face plate 10 but for only a portion of the distance thereof, while the upper portion of the face plate 10 below the portion 14 is also inwardly curved, as at 15. This inwardly curved portion 15 is formed with a slot 16, the lower margin of which is toothed, as at 17.

Extending transversely across the member 10 behind the face plate thereof is a rod 18, and slidably mounted upon this rod 20 is the inner end of a curtain roller supporting bracket 19. Disposed on one side of this curtain roller supporting bracket and coiled around the rod is the spring 20 which yieldingly holds the rod against inward movement. If it be desired to adjust the bracket 19 inward, the bracket is slid over the rod 18 in one direction or the other with or against the action of the spring 20 and then held in this adjusted position by shifting the rod 25 downward against the teeth 17. The outer end of the bracket 19 is formed so as to support the roller of a panel curtain. The weight of this roller and the curtain will, of course, hold the bracket down in engagement 30 with the teeth 17 and thus prevent any accidental release of the curtain rod which would permit it to shift.

Extending across the slot 12 and extending beneath the plates or strips 11 is a cross bar 21. This member 10 is also recessed at its upper end, as at 23 behind the slot. Adapted to be engaged in the pocket thus formed and guided by the lateral edges of the strips 11 is a curtain rod support comprising an angular strip of metal, designated 24, having a vertical arm and a horizontal arm. The vertical arm 25 has attached to its rear face the strip 26, while the horizontal arm 27 is provided at intervals with outwardly projecting lugs 28, preferably somewhat elliptical in cross section, and vertically perforated, as at 29. I have illustrated three of these lugs but the arm 27 may be provided with any number 35 of these lugs.

In the use of this device, the arm 25 is slid down into place in the recess 23 and beneath the overhanging margins of the side strips 11, as shown in Figure 4, with the portion 26 overlapping the cross bar or cross piece 21, the lower edge of the arm resting upon this cross piece, the cross piece thus acting as a stop. The arm 27 under these circumstances will be disposed slightly above 40 the upper edge of the member 10 and will

project out laterally therefrom, as shown in Figures 3 and 4. Curtain rods 30 of the character illustrated in Figure 12 will be used in conjunction with the lugs 28, these curtain rods being angularly bent at their ends and being tubular so as to fit over the lugs 28 in an obvious manner and be held by pins passing downward through perforations 31 in the extremities of the curtain rod and through the perforations 29 in the lugs. 45 It will be understood, of course, that these curtain rods 30 are each formed in two telescoping sections and that these are forms of curtain rods commonly found on the market and, therefore, requiring no further description or illustration. I have illustrated two of these curtain rods in use in Figure 2, but my device is equipped so that three curtain rods may be used if desired.

For the purpose of supporting the roller of the shade C, I have illustrated one side wall of each member 10 as being recessed at 32 to receive the slotted shank 33 of the shade roller support 34 (see Figure 10). This slotted shank slips into this recess 32 and beneath one of the strips 11 and is held in place by a bolt or set screw 35 engaging in a block 35^a. As shown in Figure 10, this shade supporting member is angular in form so that the shade supporting portion 34 may extend into the window space parallel to the jambs B. The extremity of the portion 34 is apertured or otherwise formed to receive the trunnions on the ends of the shade roller in an obvious manner. It will be obvious that by loosening the screw 35 this member 32 may be adjusted in or out so as to accommodate rollers of different lengths. Different sizes of supports 34 will be provided. It will be noted from Figure 2 that the brackets 34 while, when placed as shown in Figure 2, extend into the recess of the window so as to support the curtains C within the jambs B, yet these brackets can be inserted so as to project outward and receive the window shade, in which case, of course, the rod A is omitted, or in case no shade is desired within the window recess and a shade is mounted in the brackets 19, the brackets 34 may be removed entirely. The same is true with regard to the brackets 27, which may be used or not as desired.

For the purpose of supporting these members 10 upon the facing plates A of the window, I have provided a supporting block 36 (see Figure 9), which supporting block is rabbed at its side edges, as at 37, these rabbets extending down the block nearly to the lower end thereof but terminating short of this lower end so as to provide laterally projecting shoulders 38. This block is apertured, as at 39, for the passage of screws whereby the block may be held to the window casing and is recessed, as at 40, at its 45

upper and lower ends. These devices 37 are attached to the window facing A adjacent the upper end thereof and then in order to attach the members 10 to these 5 blocks the blocks are inserted in the enlargements 13 of the slots 12 and then the members 10 are shifted downward into the position shown in Figure 4, thus locking the blocks within the recesses of the members 10 and 10 supporting the members 10 upon the shoulders 38. Thus it will be obvious that the device may be readily applied or readily removed. When it is placed it affords a support for the shade roller if one is used, but if 15 a shade is not used the shade support 34 may be readily removed so that there is no ugly projection or protuberance. The brackets 19 afford supports for the panel curtain rollers now in considerable use. The member 20 24 may support a plurality of curtain rods 30, as illustrated in Figure 2, where two of these curtain rods are shown, one of these curtain rods being perhaps used for the support of the valance, while the other curtain 25 rod is used for the support of the relatively long side curtains or curtains of other like material now commonly used. It will be seen that the curtains are all supported exteriorly to the shade C and that 30 many combinations of curtains may be arranged for by the use of this curtain rod support.

In Figure 13 I have illustrated supporting blocks of a like character to those shown in 35 Figure 9, but in this form the blocks 36^a are provided with bolts 41 which are to be embedded in the masonry, brickwork, concrete or like material forming the wall of the window opening after a hole has been 40 drilled, the opening being afterwards filled with plaster of Paris, cement or like material around the bolt head so as to hold the supporting blocks firmly in place.

It will be understood that the roller supports 34 will be made in various sizes so as to suit the various depths of window casing and support the shade roller 34 in proper position within the window casing at all times. It will also be understood that a 45 mere curtain rod might be supported upon the brackets 19 in place of a roller carrying the panel curtain, if desired. By adjusting the brackets 19 in the slots 16, the brackets 19 are adapted to support panel curtains 50 of various widths, the spring 20 urging the brackets each in one direction and carrying the brackets against the flat faces of the ratchet teeth 17. Obviously if the shade roller C is not needed within the window 55 frame, as illustrated in Figure 2, this shade roller might be mounted upon the brackets 19, thus doing away with the use of panel curtains at this point. Where panel curtains are used, they may be mounted upon 60 a shade roller D, as shown in Figure 2, hav-

ing outwardly projecting pins or small hooks driven into the old style shade rollers whereby to hook the lace curtains or panel curtains onto the shade rollers mounted on the brackets 19. 70

While I have illustrated certain details of construction and arrangement of parts which I regard as particularly effective, I do not wish to be limited thereto as it is obvious that many minor modifications 75 might be made without departing from the spirit of the invention, nor do I wish to be limited to the particular manner of constructing the member 10, as this might be cast or stamped out of thin metal or otherwise formed. 80

I claim: —

1. A curtain support of the character described comprising two like coacting supporting members, each having means whereby it 85 may be detachably engaged with the facing of a window casing at opposite sides of the window opening, each of said members being hollow, a transversely extending rod mounted within each of said members and the face of each member being transversely slotted and the slot being toothed, a bracket pivotally mounted on each rod and extending through said slot and having slight vertical movement therein and when lowered 90 engageable with the toothed edge of the slot to hold the bracket in adjusted position, and a spring surrounding the rod and engaging on one side of the bracket to urge the bracket in one direction. 95

2. Means for supporting curtains on window casings comprising two coacting like supporting members, each of said members being hollow and formed with a front piece and a back having a longitudinally extending, medially disposed slot, the slot being enlarged at its lower end, shade or curtain supporting brackets mounted upon each of said members, supporting blocks adapted to be engaged with a window casing, each 105 block being rabbetted upon its lateral edges and being formed with stops at the lower ends of the rabbets whereby each of said supporting members may be engaged with the block by inserting the block in the enlarged end of the slot and shifting the member downward. 110

3. A curtain and shade support of the character described comprising two like members adapted to be applied to the face of the window casing at opposite sides of the window opening, each of said members being hollow, a supporting device for each part adapted to be attached to the jambs of the window frame, each member having means on its rear face to engage the corresponding supporting device, curtain or shade supporting brackets attached to said members, means for supporting the shade roller upon said members comprising angu- 120 125 130

- 4
- lar brackets, one arm of each bracket being longitudinally slotted, the side wall of each bracket being slotted to receive the slotted arm of the bracket, and a detachable screw 5 passing through the rear wall of the member and into said slot whereby the bracket may be adjustably engaged with the member and capable of being inserted so as to extend either rearward or forward.
- 10 4. A curtain supporting device of the character described comprising a pair of like supporting members, each of said members being hollow and having a longitudinally extending slot in its back, the lower 15 end of the slot being enlarged, attaching blocks adapted to be attached to the window casing and insertible through said enlarged portion of the slots and having slid-
- ing engagement with the walls of said slots whereby to support said members upon the facing, said members intermediate their ends being each provided with a transversely extending toothed slot, supporting brackets for said members, each having its shank extending through the slot of the 20 corresponding member and mounted within the hollow interior of the member for lateral adjustment, and angular brackets adapted to support curtain rollers, each having a downwardly extending leg having 25 a sliding engagement with the walls of the longitudinally extending slot of the corresponding member.

In testimony whereof I hereunto affix my signature.

EVERETT A. BURNS.
